UNITED STATES PATENT OFFICE

2,461,373

ONE-MAN POSTHOLE DIGGER

Clarence M. Cox, Belgrade, Mont.

Application July 18, 1947, Serial No. 761,959

1 Claim. (Cl. 255—19)

1

This invention appertains to novel and useful improvements in devices utilized particularly in obviating a portion of the labor involved in digging holes, particularly for posts, poles and the like.

An object of this invention is to provide means for journaling a frame member on a tractor or some other prime mover, said means characterized by arcuately contoured tracks permitting a predetermined travel about the longitudinal axis of said frame.

Another object of this invention is to provide means for selectively raising and lowering said frame and means for resiliently biasing said raising and lowering means.

Another object of this invention is to provide an improved bracket at the end of the said frame having a perch pivoted thereto and means for retaining an auger in said perch while the perch has associated therewith means for pivotally adjusting the same.

A further object of this invention is to provide means for adjusting the auger retaining means through a predetermined travel in order that the said auger means will always be substantially perpendicular to the grade line.

A further object of this invention is to provide an improved drive shaft means which is telescopingly adjustable as well as a slip clutch means which is over ridden under predetermined values of torque.

A still further object of this invention is to provide an efficient device of the character described which operates smoothly, rapidly and extremely satisfactorily.

Ancillary objects and features of novelty shall become apparent to those skilled in the art, in following the description of the preferred embodiment of the present invention, illustrated in the accompanying drawings, wherein:

Figure 1 is an elevational side view of the preferred form of the present invention showing the same in use with a conventional tractor;

Figure 2 is a plan view of the invention disclosed in Figure 1;

Figure 3 is a plan view of the actuating and control mechanism forming part of the present invention;

Figure 4 is a fragmentary plan view of the detail of construction shown in Figure 3 with parts removed for clarity;

Figure 5 is a longitudinal sectional view of the invention disclosed in Figure 3 and taken substantially on the line 5—5 thereof and in the direction of the arrows;

2

Figure 6 is an enlarged perspective view of the tracks and pivot means used in conjunction with and forming part of the present invention;

Figure 7 is a longitudinal sectional view of the slip clutch member forming part of the present invention and showing telescopic drive shaft associated therewith;

Figure 8 is an enlarged plan view of the bracket and perch with other associated mechanisms disclosed in Figure 2;

Figure 9 is a front view of the detail of construction shown in Figure 8 showing various positions of the auger retaining means by utility of phantom lines;

Figure 10 is an enlarged detail of construction showing primarily the auger retaining means;

Figure 11 is a perspective view of the slotted channel positioned between members of the frame;

Figure 12 is a transverse sectional view of the invention disclosed in Figure 11 and taken substantially on the line 12—12 thereof and in the direction of the arrows;

Figure 13 is an enlarged plan view of the resiliently biased bracket used in conjunction with the auger retaining means and forming a part thereof;

Figure 14 is an enlarged longitudinal sectional view of the pivot means disclosed in Figure 8 and taken substantially on the line 14—14 thereof and in the direction of the arrows, and;

Figure 15 is an elevational side view of the transmission and housing means forming part of the present invention, parts being broken away in section to disclose details of construction.

Referring now in detail to the illustrated preferred embodiment of the present invention, like reference characters are used throughout to indicate similar elements thereof.

40 This invention has been conceived and developed to provide a device which is primarily an attachment for tractors or other prime movers. One of the main purposes of the present invention is to provide a device which is readily attachable to conventional tractor and which may dig holes extremely rapidly and accurately. The present invention is capable of digging holes in a straight line over any type of terrain on which a tractor may successfully operate. By use further of the present invention, the operator of the tractor need not turn tractor around or adjust the tractor to suit the said terrain since all the adjusting is carried out in the present invention.

45 Figure 1 is an elevational side view of the preferred form of the present invention showing the same in use with a conventional tractor;

50 Figure 2 is a plan view of the invention disclosed in Figure 1;

55 A frame 10 composed of a pair of rods 12 and

14 respectively is provided with tie members 16 and 18 for supporting said rods in a substantially triangular relation. Braces 20 and 22 are also provided on said frame for the obvious purpose of stiffening the same.

A support is provided on the tractor for the purpose of receiving various control members and links thereon. This said support may be seen in Figures 2, 3 and 4 and is composed of various bars whose function and purpose will be brought out as the description proceeds. Going to Figure 1, there is disclosed a short member 26 welded or otherwise secured to the member 28 (forming a portion of said support). It will be noted from an inspection of Figure 1 that the elements 26 and 28 are associated with a flat metal bar 30 which rests upon a draw-bar 32. The element 30 is detachably secured to the said draw-bar 32 by conventional bolts 34. These bolts afford a rapid means for detachably receiving the invention on a tractor.

A bracket 36 is secured to the terminal portion of the frame members 12 and 14 and supports 38 are utilized in assisting to retain the said bracket in a fixed position. These members 38 are fastened to the frame 10 by means of a pin 40 which extends to each of the said members 38 and through the frame member 10. A perch 42 is pivotally received on the end of the said bracket 36 by any suitable conventional pivoting means such as the short bolts 45.

Means for pivotally mounting an auger or other digging instrument is provided on the said perch 42. It is noted at this point that the auger retaining means to be described subsequently is so balanced and pivoted that it assumes the behavior of a pendulum, or waist being drawn vertically downward by the force of gravity. Of course, this is true only when not acted upon by some outside force such as the various adjustments within the purview of this invention. A back plate 46 is secured to a selected portion of the said perch 42 by any conventional means such as bolts 48 and a slide member 50 is received therebetween. This slide member has a clamp 52 formed therein and a locking bolt 54 associated with the said clamp.

A relatively heavy gear case 56 is received within the clamp 52, the said clamp engaging suitable shoulder portions 58 for a firm grip.

A U-shaped member 60 having bolts 62 extending through the legs thereof is resiliently mounted to the bracket 36. This resilient mounting consists of a rod 64 extending through the bracket 36 and through the U-shaped member 60. A spring is then interposed between the said bracket and the said U-shaped member. Of course, this spring constantly biases the said U-shaped member 60 from the bracket 36. The screws 62 engage the gear case 56 just below the gear receiving enlargement therein. (See Figure 1).

A slotted plate 68, see Figure 8, is rigidly received between the said frame members 12 and 14 and partially held therein by the utility of the above described bolts 40. In securing the said bracket 36 to the members 12 and 14, a strap 70 extending beneath the said bracket 36 and around the members 12 and 14, not only assists in retaining the said bracket 36 but also helps to secure the plate 68 in the desired location. A strap 72 is also received around the gear case 56 and it is about this point that the gear case is pivoted. A bolt 74 extends through the strap 72 and embraces the said gear case thereby hold-

ing it in a relatively immovable relation with the said strap. A second bolt 76 extends not only through the strap 72 but also through a slot 78 in said plate 68. Of course, washers 80 may be interposed in the system wherever sound engineering dictates. Reference is made particularly now to Figure 14 wherein the particular pivot means shows up in detail. A rotating member 82 is journaled on the shaft 76 and is provided with sloping spaces. The interior portion of the said rotating member slopes to the smallest value and it is at that point that the slot 76 engages the rotating member. Of course, it may be readily appreciated that several types of motion are permitted of in this type of pivot. Pivotal travel is permitted about the longitudinal axis of the member 68 as well as rotative motion about the shaft or bolt 76 as an axis. Since the gear case has been described as secure to this point (the strap 72) the above mentioned pivotal or pendulum-like motion is permissible. The said gear case 56 may assume positions as shown in the dotted lines of Figure 9. Also in Figure 9 it is apparent that a plurality of apertures 86 are provided for the purpose of receiving sundry equipment therein, if so desired.

Taking now Figure 1, there is disclosed a plate 38 secured to the said member 28 (forming part of said support) and arcuate tracks 90 having a slot 92 therein is secured to said plate 38. There are two of these constructions provided, oppositely disposed, for the purpose of receiving and guiding the said frame links or members 12 and 14 respectively therein. Brackets 94 are secured to each of the said frame members 12 and 14 and lugs 96 project therefrom. These lugs are received in the said slot 92 and act as riders therein.

An anchor member 98 is supplied in the said support and an arcuate friction disc 100 is secured thereto. A lever 102 is pivoted to the said anchor member 98 and engages the said disc 100. Pitman rods 104 extend from portions of the said lever 102 to the lugs 96. Inspection of Figure 3 clearly discloses this structure. It will be noted from this figure that by urging the lever 102 about its pivot point, the frame member 10 may be rotated about its longitudinal axis in order to tilt the gear box 56 to a selected position. In certain types of farm land and over certain types of terrains, tractors lean to various angular inclinations and the angle might be greater than can be compensated by the above described pivotal movement. When this is the case, the bar 102 may be pulled and set to a certain value of angularity thereby permitting holes to be dug parallel to the pull of gravity.

Means are also provided for pivoting the perch 42 about the pivot point 45 as an axis. This means consists of a collar 108 secured to the upper portion of said gear box 56 and a rod 110 secured thereto. The other end of the said rod 110 is engaged in a suitable clamp 112 which is itself seated on a crank 114. This crank 114 is pivoted to the member 28 by means of a bolt or some other suitable pivot pin. Of course, by actuating the lever arm or crank 114, the force is transmitted through the gear box 56 to the bracket-held perch 42. This adjustment is provided for the obvious purpose of ascertaining proper results when the tractor pitches due to one end thereof entering a hole or sharp incline.

There is provided means for lifting the entire frame, gear box and other associated mechanisms about the lugs 96 as an axis. This control is

effected by means of the following structure: Eye bolts are utilized in retaining the braces 38 to the bracket 36. These eye bolts 116 receive a chain or other securing means 118 therein. After joining to a single actuating cord 120, the said cord extends about a pulley 122, situated on the member 28 thence about a sheave 124. This sheave is secured to a shaft 126 which is journaled between the support 98 and support member 28. A crank 129 is pivoted to the support 98 and a cable 130 is secured thereto and around a collar 132 also secured to the shaft 126. Of course, by pivoting the crank or lever 129 about its pivot point 134 the cord 120 may be wound around the sheave 124 thereby lifting or lowering the frame 10. A resilient biasing means, preferably a spring 136 is secured between the crank 129 and a suitable bracket 138, secured to the support 98. By this expedient, an efficient, economical and satisfactory return means is provided for the frame-lifting device.

Inspection of Figure 4 discloses a pulley 140 secured to the shaft 126, which pulley might be utilized with a belt 142 to assist in lifting the frame 10. Of course, the belt 142 could conventionally be secured to a suitable power take-off provided in the majority of conventional tractors.

Going now to the auger which is preferably employed in this invention, a conventional one 145 is utilized. The gear box 56 is provided with a central shaft 146 having a beveled gear splined or otherwise fixed thereto. Of course, suitable thrust bearings, unshown, are associated with the shaft 146 for retaining the same in the desired position. The said shaft 146 is provided with upper and lower splined terminal portions for easily and conveniently receiving the auger at one end thereof. The splined portion 150 of the shaft 146 may be provided with an aperture therein for receiving a set screw 152 therethrough which also extends through the auger 145. This construction permits of detachable relation relative to securing of the auger to the shaft 146. A second shaft 156 is suitably journaled in the said gear box 56 and a bevel gear 158 is secured to a terminal portion thereof. This last mentioned bevel gear engages the said bevel gear 148 and is drivingly connected thereto. A bifurcated member 159 is provided at the other end of said shaft 166 and forms a part of the universal joint 160. The mating portion of the said universal joint 160 is provided on a drive shaft 162. Inspection of Figure 7 discloses that the said shaft 162 is also splined at the end thereof and a collar 164 is telescopically received on the splined portion 166 of said shaft. Of course, the collar has splined bore 168 permitting of slideable, telescoping engagement between said sleeve and said shaft.

A slip clutch is provided in this connection. This slip clutch may be made in the following manner. The end portion of the said sleeve 164 is threaded at 170 and a nut 172 is provided thereon. A spring, of a predetermined tensional value 174 engages the said nut 172 and a collar

176 which is itself splined to the sleeve 164. This last mentioned splined connection is effected by the utility of a pin 178 in suitable slots provided not only in the sleeve 164 but also in the collar 176. Gear teeth 180 are provided on the collar 176 and on a plate 182. This plate has a reduced extension 184 protruding therefrom which is journaled in a bore 186, in said sleeve 164. Of course, by this construction when a predetermined torque is applied to the said shaft 162, the clutch will be overridden. There will be noted a bifurcated extension 188 on said plate 182 which also forms a portion of the universal joint. This universal joint 190 extends through a suitable, conventional power take-off of the tractor which is employed in operation of the invention. Due to the various adjustments described above, this type of drive shaft which is extensible, is an essential feature in the present invention.

20 Certain braces 196 are secured between the control assembly or support for the purpose of lending rigidity to the invention.

25 While there has been described and illustrated but a single preferred embodiment of the present invention, it is apparent to those skilled in the art, that various changes including omissions, additions and rearrangements of elements may be made herein without departing from the spirit of the invention. Accordingly, limitation is 30 sought only in accordance with the scope of the following claim.

Having described the invention, what is claimed as new is:

35 A hole digger comprising a frame, a support adapted to be secured to a tractor having arcuate tracks thereon with slots in said tracks, lugs projecting from said frame and disposed in said slots, a lever pivoted to said support, pitman rods connecting said lever and said frame to rotate said frame, a bracket secured to said frame, a perch 40 pivoted to said bracket, a housing with a transmission therein pivotally mounted on said perch for supporting and actuating an auger, means for pivotally adjusting said perch comprising a rod secured to said auger retaining means, and a 45 crank pivoted to said support receiving said rod, an extensible shaft, a spring urged clutch in said shaft, and means drivingly connecting said shaft and said transmission, a flexible member attached to said frame, and means mounted on said support for winding and playing out said flexible member to raise and lower said frame in a pivotal manner about said lugs as an axis.

CLARENCE M. COX.
